UNITED STATES PATENT OFFICE.

ROBERT D. H. ANDERSON, OF BOSTON, MASSACHUSETTS, ASSIGNOR TO FRANK RIDLON COMPANY, OF BOSTON, MASSACHUSETTS, A CORPORATION OF MASSACHUSETTS.

ELECTRIC-LIGHT STAND.

1,222,915.

Specification of Letters Patent. Patented Apr. 17, 1917.

Application filed August 13, 1915. Serial No. 45,343.

To all whom it may concern:

Be it known that I, ROBERT D. H. ANDERSON, of Boston, in the county of Suffolk and State of Massachusetts, a citizen of the 5 United States, have invented a new and useful Improvement in Electric-Light Stands, of which the following is a specification.

My invention relates to a stand for electric lighting and is more especially constructed for use in photographic work where considerable adjustment is required and where the socket mechanism for the lamps is quite large and heavy. The details of my invention comprise chiefly a combined clamp 15 and adjusting device whereby the height of the stand may be adjusted and clamped in place when in proper position, and the direction in which the light is thrown may be changed.

20 My invention will be understood by reference to the drawings, in which—

Figure 1 is an elevation of a stand embodying my invention.

Fig. 2 is a section showing the adjusting 25 and clamping mechanism.

Fig. 3 is a section on the line 3—3 of Fig. 2.

Fig. 4 is a top view of the adjusting and clamping mechanism, the top of the housing 30 being removed.

Fig. 5 is a vertical section of the lower part of the stand.

Fig. 6 is a top view of the mechanism for 35 adjusting the lamp with relation to the object.

Fig. 7 is a section on the line 7—7 of Fig. 6.

Fig. 8 is a section on the line 8—8 of Fig. 9 showing an arrangement of clamps where 40 three heads or sets of lights are to be used, each being separately adjustable.

Fig. 9 is a side elevation of a mechanism shown in Fig. 8.

Figs. 10 and 11 are modifications of the 45 lifting mechanism.

A is a base supported on casters a or otherwise, and having a socket A^1 at its upper end and in which sets a sleeve B held in place by a set screw a^1 . Within this sleeve 50 is a tube C, the upper end of which is horizontal and terminates in a coupling D to be described below and by which the lamp socket or sockets are supported, their location being represented by the lamp shade 55 E within which they are. This shade and

the lamps inclosed in it being of ordinary construction, need not be further described.

The cable to supply current is shown at e and passes up through the tube C to the lamps. At C^1 is shown the casing of an 60 ordinary electric switch which need not be described further as it is common in the art. The cable is connected to the terminals of the switch C^1 in the ordinary way so as to control the light at E.

65 The main purpose of my invention is to simplify the raising and lowering of this tube C so as to raise or lower the lamps within the shade E. For this purpose I have provided a housing F which is attached 70 by a set screw b to the upper end of the sleeve B. Within this housing is journaled a shaft g carrying a roll G which is preferably shaped as shown (see especially Fig. 4) so as to have a considerable bearing upon 75 the outer surface of the tube C. The shaft g terminates in a crank G^1 so that by turning the crank in either direction the roll G will be turned in a direction to raise or lower the tube C as the case may be. To cause the 80 motion of the tube C to be in a right line the tube is grooved as at c and a pin f is passed through the housing F and is adjusted to lie in this groove so as to prevent the tube C from turning. Means should also 85 be provided to keep the tube in proper frictional relation to the roll G. For this purpose I prefer to provide on the opposite side of the housing F from the roll G a set screw h which is adapted to engage a carriage H 90 located within the housing and having two rolls H^1 , H^2 , each in shape like the roll G but smaller, each being thus adapted to have considerable bearing surface on the tube C. This carriage has a center h^1 upon which the 95 end of the screw h bears to keep the carriage in place, and the screw has a handle h^2 by which it may be turned. The function of this carriage is two-fold. Upon applying pressure thereto by means of the screw h 100 its rolls H^1 , H^2 are forced against the tube C and force the tube against the roll G. By this means sufficient frictional contact may be supplied between these three rolls and the tube C so that upon turning the crank G^1 105 the roll G may be caused to raise or lower the tube C depending upon the direction in which the roll G is turned. When the height of the lamp has been properly adjusted, if the lamp is sufficiently heavy to require it, 110

the screw h may be given a further turn so that the rolls G , H^1 , H^2 become a clamp and hold the tube C in its adjusted position, although under ordinary conditions this is not necessary. I prefer to provide a cover F^1 to the housing F connecting it thereto by screws f^1 .

In assembling this apparatus I provide a cable e sufficiently long for all possible contingencies, and I provide the base with a flooring a^2 on which the surplus of cable may rest.

When therefore (presuming this standard to be used for photographic purposes) it is desired to change the height of the lights it is only necessary to turn the roll G in either direction to raise or lower the tube C as the case may be.

In the adjustment of such a light it is often necessary that it be turned to throw the light either up or down, and it may be desirable to throw it to one side or the other. For this purpose I have provided the coupling D which is shown in detail in Figs. 6 and 7, and as to some of its features is described in Letters Patent of the United States No. 1,077,663, dated November 4, 1913.

Upon the upper end of the tube C , which is preferably bent at its upper end into a horizontal position, I attach by a threaded neck a saucer-shaped member J . This member has a threaded opening through its center and into that opening is carried a short sleeve or hollow bolt j threaded at each end, its middle portion being smooth. Onto the smooth portion of this sleeve is slipped a bracket member J^2 which carries a saucer-shaped member J^1 which engages the member J so that a cavity is formed between the members J and J^1 . The rim, so to speak, of each of these saucers is beveled so that a narrow bearing surface is provided in each member against which the other member bears. The bracket J^2 is capable of rotation around the sleeve j and may be clamped against the member J by nuts j^1 which are screwed onto the outer threaded end of the sleeve j . By this means an adjustment around the axis of this portion of the tube C may be effected, the contacting surfaces of the parts J and J^1 being quite narrow and smooth so that the part J^2 may slide against the part J without difficulty when the nuts j^1 are loosened.

The bracket J^2 is provided with a second similar saucer-shaped portion J^3 which lies at right angles to the portion J^1 and has an opening j^2 through it so that the cable e may be led through this opening. A cover J^4 similarly shaped is attached to the member J^3 by a bolt j^4 and nut j^5 and carries a threaded neck J^6 to which the socket or sockets may be attached and out through which the cable passes to sockets, this neck being hollow as shown and threaded on the

exterior for this purpose. The contacting edges of J^3 and J^4 are also narrow and smooth so that one may turn on the other and so adjust the direction in which the light is to be thrown. The angle of the lamp E to the vertical portion of the rod C may readily be changed. The nuts j may be set up sufficiently to hold the parts in place and yet allow them to be turned by hand.

A number of these lamps may be mounted on the same standard, and I have shown in Figs. 8 and 9 a construction where three lamps are mounted about the central sleeve B in the manner above described. The only modification necessary in the construction described above, to apply three sets of adjusting mechanism and clamps in this case, is in the shape of the housing which I have marked F^2 , the cover being F^3 , f^2 in Fig. 8 showing the screw holes by which the cover F^2 is attached to the housing. In this case, however, but one sleeve B is used, the tubes C being carried outside the sleeve B instead of inside it, as in the case where a single lamp is used. The cables in this case pass up through suitable openings in the base A and through the tubes C as before.

It will be evident that the tube may be raised and lowered in other ways than that above described. For example, in Fig. 10 the housing, marked in this case F^4 , is differently shaped and the roll in this case is shown as a sprocket G^2 around which passes a sprocket chain g^1 which is attached to a collar g^2 clamped to the bottom of the tube C . The wire cable is not shown in this view, but passes as before from the base A up through the tube. A crank G^1 is attached to the axle g^3 of the sprocket G^2 , and after the proper adjustment is made the crank handle may be locked in any convenient way. In this view, however, as well as in Fig. 11, instead of applying a lock to the crank directly I slot the housing as at F^6 through the bearing for the shaft g^3 and provide a thumb-screw g^4 by which the two sides of this slot may be brought together to clamp the shaft. F^5 is the top of the housing which as before is attached to the housing by screws f^1 .

In Fig. 11 another modification is shown in which instead of a sprocket G^2 a pinion G^3 is in like manner mounted on a shaft g^3 in a housing F^4 provided with a top or cover F^5 attached thereto by screws f^1 . The tube in this case is provided with a rack g^2 with which the pinion G^3 engages. In this case also a crank and handle G^1 is attached to the shaft g^3 of the pinion G^3 . In both of these cases the sleeve is attached to the base by screws a^1 and the housing is attached to the top of the sleeve B by screws b^1 . In each case the tube C may be grooved as at c and a pin f may be provided so that the tube C 130

will be moved in a right line. The clamping mechanism is as shown in Fig. 10, this clamping mechanism being applicable to the devices of the other views if desired.

5 It is evident that my invention may be embodied in other ways, its purpose being to provide a simple and easy means of raising, lowering and clamping the light supports comprising the tubes C so that the 10 height of the lamp or lamps may be easily adjusted and will not easily get out of adjustment, my invention also comprising means for adjusting the angle of the lamps to the object upon which light is to be 15 thrown.

It is to be understood of course that in the forms of my invention shown in Figs. 8, 9, 10 and 11 the lamp is to be supported as 20 shown in the other figures or in some equivalent way so that their adjustment may be easily accomplished.

What I claim as my invention is:—

1. In a device of the kind described, a standard comprising a sleeve, a hollow sliding member movable in said sleeve and carrying a lamp socket at its upper end, electric connections leading to said lamp sockets, and means to raise and lower said sliding member and to automatically lock the 30 same, said means comprising adjustable friction rollers adapted to engage said sliding member.

2. In a device of the kind described, a standard comprising a sleeve, a hollow sliding member movable in said sleeve and carrying a lamp socket at its upper end, electric connections leading to said lamp sockets, and means for raising and lowering said sliding member and comprising adjustable friction rollers mounted on opposite sides adapted to engage said sliding member, one of said friction rollers being mounted on a crank shaft, and means for operating said crank shaft.

45 3. In a device of the kind described, a standard comprising a sleeve, a hollow sliding member movable in said sleeve and carrying a lamp socket at its upper end, electric connections leading to said lamp 50 sockets, and means to raise and lower said sliding member comprising a housing, a shaft

mounted therein, a roller supported upon said shaft to have frictional contact with said sliding member, adjustable coöperating means therein to retain said roller in contact 55 with said sliding member, and means for rotating said roller to raise and lower said sliding member substantially as described.

4. In a device of the kind described, a standard comprising a sleeve, a hollow sliding member movable in said sleeve and carrying a lamp socket at its upper end, electric connections leading to said lamp sockets, and means for adjusting the height of said lamp sockets mounted on said sleeve 60 and comprising a roller and means for supporting it in fixed position, and means adjustable with relation thereto adapted to engage said sliding member and force it into contact with said roller, said means comprising 65 a carriage having rolls adapted to engage the sliding member on the side opposite said roller and means for adjusting said carriage radially to said sliding member, and means for rotating said roller.

75 5. In a device of the kind described, a hollow standard, a lamp holder and means for supporting said lamp holder on said standard comprising a member having a neck adapted for attachment to said standard, a hollow sleeve threaded into said member, said sleeve having a portion of its periphery smooth, a second member adapted to turn upon the smooth portion of said sleeve and means for confining it thereon, said 80 members being in frictional contact whereby the second member may be turned about said sleeve as an axis, said second member carrying a bracket and a member having a circular bearing, a rotatable member having a 85 complementary bearing adapted to engage with said circular bearing and having a hollow neck whereby a lamp socket may be attached thereto, said supporting means as a whole being hollow whereby a cable may 90 be threaded through it from said standard 95 to said lamp socket.

ROBERT D. H. ANDERSON.
